UNITED STATES PATENT OFFICE

2,348,151

PUMP

Lutwin C. Rotter, Maplewood, and Victor G. Klein, St. Louis, Mo., assignors to Lincoln Engineering Company, St. Louis, Mo., a corporation of Missouri

Application May 26, 1941, Serial No. 395,136

3 Claims. (Cl. 222—75)

This invention relates to pumps, and with regard to certain more specific features, to improvements upon the pump disclosed in the United States Patent 2,280,708 of Victor G. Klein and Jonathan Kludt, dated April 21, 1942, for Pump.

Among the several objects of the invention may be noted the provision of a pump for pumping heavy, semi-plastic and similar materials from containers to applicator nozzles and the like; the provision of apparatus of the class described which eliminates spouting at the start of application and which provides for a continuous and even flow after said start; and the provision of apparatus of the class described which obtain said results with materials of various heavy consistencies requiring various substantial delivery pressures. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a perspective view showing in dotted lines a commercial drum from which pumping is accomplished;

Fig. 2 is a longitudinal section of a flow control pump;

Fig. 3 is a fragmentary right-side elevation of Fig. 2, parts being broken away;

Fig. 4 is a section taken on line 4—4 of Fig. 2;

Fig. 5 is a plan view of a control nozzle;

Fig. 6 is a vertical section taken on line 6—6 of Fig. 5;

Fig. 7 is a left-end view of Fig. 6;

Fig. 8 is a diagrammatic vertical section of a control valve;

Fig. 9 is a view similar to Fig. 8 showing the valve set to an alternative position; and

Fig. 10 is a diagrammatic view showing typical relative size ratios of certain parts for obtaining the results desired.

Similar reference characters indicate corresponding parts throughout the several views of the drawings.

Said Patent No. 2,280,708, shows broadly an open commercial container located in a supporting frame. On the top of the frame and above the container is a cylinder wherein is a pneumatic piston. This piston is operable up and down at will by introduction of air below or above

it, and by means of a piston rod supports an assembly of an engine, pump and follower plate. During operation, the follower plate rests upon the surface of the viscous material in the container and is biased down by the sum of the weight of the pump and engine and the force of any air introduced above said piston. Operation of the engine causes the pump to withdraw material through a central opening in the follower plate and force the material to an outlet. As the material is exhausted from under the follower plate the plate which is loosely fitted into the container descends into the container and thus always places priming pressure upon the material as it enters the pump. The present device includes similar parts, similarly indexed but not shown in as great detail as in said application, since already shown in said patent application and since the improvements lie in features applied to the stated broad outline of parts.

Referring now more particularly to Fig. 1, there is shown at numeral 1 a commercial container for semi-plastics, such as luting or caulking compounds, putty, or the like. It is desired that these be smoothly exuded from a nozzle N, directly to the point of use, as for example in glazing or sealing cracks, etc.

Numerals 3 and 5 show supporting plates between which are spacing and supporting pillars 7. These form a supporting frame in which are tension holders 101 for the container 1.

On the upper plate 5 is carried a manifold 9 which in turn supports a lift cylinder 11. In the cylinder 11 is a vertically moving piston 13 located on the upper end of a piston rod 15. The rod 15 extends down through a suitable packing gland in the manifold 9. Below plate 5, the rod 15 dependently supports an assembly of a reciprocating air engine 41, a pump 53 and follower plate 63. The engine drives pump 53 with which it is structurally organized as the unit carried on and with a follower 63. Plate 63 has a suitable central opening 64 through which material is drawn by the pump 53. All this is as set forth in said patent.

In the manifold 9 is an air inlet pipe 21 communicating with the lower end of the cylinder 11. The upper end of the cylinder also has an air inlet pipe 23. The inlets 21 and 23 pass to a control valve V (see also Figs. 8 and 9) which by the operation of a button 19 from one position to another distributes air alternatively either to the inlet pipe 21 or to the inlet pipe 23.

The valve V is shown diagrammatically in Figs. 8 and 9 wherein an air connection 22 is

shown opposite the inlet pipe 21 and a second air connection 24 is shown connected opposite the inlet pipe 23. A valve stem 26 (on which is the handle 19) has therein ports 28 and 29. Port 28 connects pipes 21 and 22 when the valve is moved to the position shown in Fig. 8 (handle 19 up). At this time an exhaust passage 31 permits exhaust from the pipe 23 while pipe 24 is cut off. In Fig. 9, port 29 (handle 19 down) connects pipes 23 and 24 while pipe 21 exhausts at 33, 10 pipe 22 being cut off. Thus the valve V affords means for applying air either below or above the piston 13, while venting the opposite side of the piston to atmosphere. Hence when the button 19 is pushed up, air flows over pipe 22, port 28, pipe 21 and to the under side of the piston 13 and lifts the piston, and also the engine 41, pump 53 and follower 63 carried on rod 15. Then a filled container 1 may be slipped into place after a former emptied container has been removed. When the handle 19 is pulled down as shown in Fig. 9, then the pipe 24 is connected with the pipe 23 by way of port 29 and air is supplied above the piston 13. This results in downward biasing force on the follower 63, in addition to the weight of the engine 41 and pump 53 carried thereon. This serves to push or prime the material beneath the follower up into the pump 53. A groove 181 and detent means 183 serve to hold the valve in said position when desired. In this case no air flows nor exhausting takes place.

Air for operating piston 13 and air engine 41 is led in over an air line 6 to a manifold 8 which supplies the pipes 22 and 24. This manifold carries a suitable pressure gauge 10. It also has an outlet 12 which passes through a solenoid valve 14 to a branch connection 16. From the branch connection, one flexible pipe line 17 leads to the air engine 41 and another branch pipe 18 leads to a valve 20 controlling flow to a second air engine 35 which is shown in Figs. 2-4 and 10. An air connection from the valve 20 to the engine 35 is indicated at 37. The engine 35 is stationary and supported upon the upper plate 5.

The air engine 35 (Figs. 2-4) consists of a cylinder 39 in which is a reciprocating piston 40 carrying a piston rod 43. The piston rod 43 drives a pump plunger 45 operating in a cylinder pump 47. A lost-motion driving connection 49 is effected between the piston 40 and a valve mechanism shown generally at G. The purpose of the valve mechanism G is to distribute and release air alternately to and from opposite ends of the cylinder 39. This valve mechanism may be any of various types and needs not be further detailed, particularly inasmuch as a similar one has been completely described in the United States Patent 2,215,852 of Victor G. Klein, dated September 24, 1940. Another such valve mechanism is disclosed in the United States Patent 2,269,423 of Frank S. Barks et al., dated January 13, 1942, for Valve mechanism. It may be noted that the D-valve per se, shown at 151, which is operated from stem 153, distributes air to inlet 155 from supply manifold 154 for driving piston 40 to drive out material from pump 47 (Fig. 2) as will appear. The opposite side of the piston 40 is at this time exhausted through passage 157 to the exhaust 159. After the piston 40 reaches the end of its driving stroke the valve 151 is automatically re-set to deliver air from 154 through 157, while exhausting air through 155 and 159. Air under pressure is supplied from connection 37 to compartment 154 via passage 156 (Fig. 4). Since the valve mechanism G, including D-valve 151

per se is in the manifold 154, the D-valve acts as a distributor of air alternately to passages 155 and 157 and alternately connects these passages 155 and 157 to the exhaust 159.

5 The stationary pump 47 receives its supply of lubricant at inlet 51 from line 95. Line 95 leads from the pressure outlet of the movable pump 53. The pressure outlet of pump 47 is indicated at 52 in connection with an outlet check valve 55. The outlet 52 is connected to a flexible lubricant hose 57 which leads to the control nozzle N.

The nozzle N is detailed in Figs. 5 to 7. It consists of a hollow handle 59 through which material flows from hose 57 to an applicator outlet 61. A control handle or lever 65 oscillates against the end 67 of a control valve 69. The valve 69 is normally biased shut by means of the spring 71 but when pushed by the handle 65 moves to open position (Fig. 6).

20 On the side of the handle 59 is mounted an electric switch 73 having contacts 75, one of which is provided with an outwardly biased operating stem 77. An extension 79 from the handle 65 cooperates with the stem 77 when the valve 69 is opened in order to close the contacts 75 and vice versa. The contacts are closed just after the valve 69 is completely open. They are also opened just before the valve 69 closes.

25 The contacts 75 are wired as indicated at 79 30 with a solenoid valve 14 through a junction box 81. The circuit is potentially energized by plugging in an outside line into the box 81. Whenever the contacts 75 are closed, the circuit is 35 closed through the solenoid valve 14 to open said valve. Opening of the valve 14 conveys air from the manifold to the branch 16, from whence it flows to the movable air engine 41 to start it and to the stationary engine 35 to start it simultaneously. It may be assumed that at this time 40 the valve V is set so as to impress pressure on the piston 13. Thus when the operator presses upon the nozzle handle 65, the valve 69 is opened and then the contacts 75 are closed. Closing of the contact opens the valve 14 so that both of 45 the engines 41 and 35 start. Hence both pumps 53 and 47 start. Pump 53 delivers fluid over the line 95 to the pump 47. Pump 47 forces the material ahead through the line 57 to flow out of the now open valve 69. No spouting occurs. When 50 the handle 65 is released, the contacts 75 open and valve 69 springs shut, whereupon no further air pressure is available to operate the pumps. The result is that the hose 57 is never under pressure unless the valve 69 is open. This feature 55 results in the elimination of the spouting action which is associated with nozzles which simply open a lubricant or material line under pressure. Such lines being composed of expansible materials spurt when opened because of the sudden contraction in the resilient hose material 60 composing the line. This disadvantage is eliminated by means of the present invention.

65 In view of the above it is clear that both pumps 53 and 47 are single acting and of the full-stroke variety and flow from pump 47 is at least equalled by the flow of from pump 53, but pump 53 reciprocates more slowly by a ratio determined by the dimensions indicated below, for example. This slower speed reduces wear on pump 53 and makes 70 it easier to prime. Pump 53 is made to reciprocate more slowly than pump 47 by employing a larger volumetric displacement for its driving engine 41 than for engine 35, and feeding both engines with the same pressure of air. The effective area ratio between piston 40 of stationary

engine 35 and plunger 45 in pump 47 is the same as the corresponding ratio in the case of movable engine 41 and pump 53, so that the outlet pressures for both pumps are the same. Thus pump 47 is not in the nature of the usual booster pump. If, for some reason it cannot forward all material which could be received from pump 53, the latter automatically slows down, because of the increase in pressure between the pumps in line 95. Exemplary dimensions are, referring to Fig. 10: Piston 38 of engine 41 has a 6-inch diameter and an area of 28.274 square inches. Plunger 36 of pump 53 has a 1-inch diameter and an area of .7854 square inch. This makes an area ratio of piston 38 to plunger 36 of 60:1.

Piston 40 of engine 35 has a diameter of 4 inches and an area of 12.566 square inches. Plunger 45 has a diameter of $\frac{1}{2}$ -inch and an area of .1963 square inch. This makes an area ratio of piston 40 to plunger 45 of 60:1. Thus, pump 47 does not act as a booster of pressure but simply breaks up the long surges of pump 53. The plunger 36 of pump 53 besides having a larger diameter than plunger 45 also has a longer stroke. The effective stroke of plunger 36 is $2\frac{3}{4}$ inches; that of plunger 45 is 1 inch. Thus, geometrically, the volume per stroke of the pump 53 is greater than that of pump 47 but per unit of time the output of the two pumps is substantially the same, since the smaller one tends to run faster, the supply of air for each being assumed equal.

One object of the invention is to have the pump 47 serve to smooth out any pulsations of flow in the hose 57. This is because the engine 35 is designed to reciprocate at said faster rate than the engine 41 but it does not boost pressure. The surges that tend to be imposed in the hose 57 by the slow-operating pump 53 are broken up by the faster but shorter surges of pump 47, as it were, substantially smoothing out the flow pulsations. This feature, taken in combination with the feature of making a smooth start by the starter control associated with the nozzle N serves to provide a smooth and even flow at the start of flow from the nozzle, as well as continually after the flow is under way.

In addition to the above I provide a regulating valve 32 in the air pipe 24 which ultimately delivers air to the top of the piston 13. This is for the purpose of regulating the downward pressure of said piston 13 on the follower 63. The purpose of this is so that ample pressure for priming may be placed upon the follower for all consistencies of pumpage. For heavier materials, the pressure may be greater. For lighter materials, it should be less and this is because the relatively lighter materials tend to exude up around the edge of the follower 63 if the downward pressure is too great. For convenience the fit between the edges of the followers such as 63 and the drum walls is relatively free. Thus the regulator 32 permits of applying the correct pressure for permitting the follower 63 to be maintained on the upper surface of a material of given consistency, rather than driving it down into said material.

Thus the biasing pressure exerted upon the follower 63 by the piston 13 is controlled, for the purpose of placing the fluid under the follower 63 under as great a pressure as possible above that of the atmosphere without deleterious effects. This tends to prime the pump 53 to the most advantageous extent possible, but no more. Thus the control valve 32 in effect controls the priming pressure available at the inlet of the pump 53.

The pump 41 may be referred to as a primary, 75

low-speed pump, and pump 35 as a non-boosting, secondary, high-speed pump. As above stated, the volumetric displacements and pressures of these pumps are equal per unit of time but the rate of operation or reciprocation of pump 35 is higher than that of pump 41. But it is to be understood that while pump 41 is not indicated herein as being a pressure-boosting pump, it could incidentally be so designed in addition to its flow-smoothing function.

In view of the above, it will be seen that the several objects of the invention are achieved and other advantageous results attained.

As many changes could be made in the above 15 constructions without departing from the scope of the invention, it is intended that all matter contained in the above description or shown in the accompanying drawings shall be interpreted as illustrative and not in a limiting sense.

I claim:

1. Pumping apparatus comprising a primary pump, a secondary pump, pneumatic means for operating the pumps including an air supply line, an outlet line, said secondary pump receiving material from the primary pump and delivering it to said outlet line, the volumetric displacements of said pumps being substantially equal per unit of time, but the rate of reciprocation of the second pump being higher than that of the first, means feeding air to both of said pneumatic 25 means, a control nozzle at the end of said outlet line, a valve in said nozzle, means responsive to opening of said valve to supply air to the air line and comprising a solenoid air valve in the air line, a switch arranged for operation with said outlet valve, said switch being adapted to open said solenoid valve when the nozzle valve is open or to close said solenoid valve when the nozzle 35 valve is closed, and air pressure means for priming said primary pump and pressure control means for said air pressure priming means.

2. Lubricant pumping apparatus comprising a primary reciprocating plunger pump connected on its suction side to a material supply, a first plunger in said primary pump a secondary reciprocating plunger pump connected on its suction side with the outlet of said primary reciprocating plunger pump, a second plunger in said secondary pump said secondary reciprocating 45 plunger pump delivering to an outlet, reciprocating air engines for operating said plungers respectively, full-stroke air-operated pistons in said engines respectively which are directly connected to said plungers respectively, the area of said first 50 plunger of the primary pump being larger than the area of said second plunger of the secondary pump, whereby for a given volumetric displacement per unit of time through both pumps the primary pump may function more slowly than the secondary pump, the air piston of the engine connected with the primary pump having an area which is in the same ratio with respect to the area of said first plunger of the primary pump as is the ratio of the area of the piston of the engine connected with the secondary pump to the area of said second plunger of the secondary pump, and a pressure air supply to both engine pistons which is at the same pressure for each, whereby the larger primary pump will operate more slowly than the smaller secondary pump in a ratio such as substantially to effect said equality of volumetric displacement per unit of time of said pumps.

3. Lubricant pumping apparatus comprising a pump, pneumatic means for operating the pump,

a lubricant outlet line, means connected with said outlet line for smoothing out surges caused by the pump and comprising a second pneumatic means, an air line feeding air to both of said pneumatic means, a control nozzle at the end of said outlet line, a lubricant valve in said nozzle, means responsive to opening of said valve to open the air line and comprising a solenoid air valve in the air line, a switch arranged for operation with

said lubricant valve, said switch being wired with the solenoid valve to open the valve when the lubricant valve is open or to close said solenoid valve when the nozzle valve is closed, air-pressure means for priming said pump, and pressure control means for said priming means operative independently of said solenoid valve.

LUTWIN C. ROTTER.
VICTOR G. KLEIN.
